INVENTOR.

Daniel Burr,
By J. B. Lawyer
Atty.

UNITED STATES PATENT OFFICE.

DANIEL BURR, OF MILFORD, DELAWARE, ASSIGNOR OF ONE-HALF TO
ALEXANDER PULLEN, OF SAME PLACE.

APPARATUS FOR DRYING AND CONSERVING FRUIT.

SPECIFICATION forming part of Letters Patent No. 288,973, dated November 27, 1883.
Application filed February 6, 1883. (No model.)

To all whom it may concern:

Be it known that I, DANIEL BURR, a citizen of the United States, residing at Milford, in the county of Kent and State of Delaware, have 5 invented certain new and useful Improvements in an Apparatus for Drying and Conserving Fruits; and I do declare the following to be a full, clear, and exact description of the invention, such as will enable others skilled in the 10 art to which it appertains to make and use the same, reference being had to the accompanying drawings, and to the letters and figures of reference marked thereon, which form a part of this specification.

15 Figure 1 is a front view of the apparatus. Fig. 2 is a transverse vertical section through the apparatus.

Like letters designate corresponding parts in both figures.

20 My invention consists in the peculiar construction, combination, and arrangement of parts composing the apparatus, substantially as hereinafter set forth, whereby either steam heat or heated air, or both together, are used for 25 heating the drying-chambers, and the apparatus is adapted either to drying or conserving fruits, and whereby different chambers may be heated and treated differently at will.

I employ a set of drying-chambers, A A, of 30 any suitable or desired construction, form, and size, and they may be placed one on top of another and side by side, as many as desired, the arrangement shown in the drawings being a suitable one. These chambers are nearly or 35 quite air-tight, and their doors a a fit closely. The fruit-trays b b in them may be placed quite closely, one above another, to obtain as much drying - surface as possible. These drying-chambers are mainly heated by a steam pipe 40 or pipes, B, which extend and double or coil under each chamber, so as to present as much heating-surface as necessary to obtain the requisite heating-power therefrom. The pipe B, after extending to and coiling or doubling under the several drying-chambers, may enter a 45 condensed-steam chamber, B', from which the water from the condensing of the steam is drawn through a pipe or spout.

Auxiliary to the heating steam pipe or pipes 50 B, I employ a hot-air pipe or pipes, C, which communicate by branches c c with the interi-

ors of the several drying-chambers, so as to admit the dry heated air from the pipe or pipes into the chambers. One furnace having a 55 heating-chamber, D, suffices to generate the steam for the steam pipe or pipes, and to heat the air to pass through the hot-air pipe or pipes, the steam-coil itself heating the air before it passes through the said hot-air pipe or pipes. Also from the interior of each drying-chamber 60 an exhaust-pipe, E, leads through short branch pipes d d, connecting with the several chambers. An exhaust-fan or air-pump, G, is connected with the other end of the exhaust pipe or pipes for drawing through the said pipe or pipes the 65 air and moisture or vapor from the drying-chambers, so as to continually have dry air in the said chambers for drying the fruit. Each connecting branch c of the hot-air pipe or pipes C is provided with a stop-cock and valve, f, to 70 exclude the hot air, wholly or partially, as desired, and each branch exhaust-pipe d is similarly provided with a stop-cock, g, so that any one or more of the chambers may be cut out from action when desired. Thus each chamber is made independent of the others.

When the fruit is to be dried in a chamber or chambers A, more or less of the heated air is admitted through the hot-air pipe to increase the rapidity of the drying. When the chambers are used for conserving fruit, no hot air is admitted, since that would shrink the fruit, which is to be avoided.

I also provide for admitting steam from the steam pipe or pipes B into the several chambers A A through branch pipes i i, each having a stop-cock, k, to admit the steam or not. This may be especially useful in conserving fruit where a dry atmosphere is not desired.

What I claim as my invention is—

1. In an apparatus for drying and conserving fruits, the combination of drying or conserving chambers, steam heating pipe or pipes leading to the several chambers, hot-air pipe or pipes communicating with the interior of the several chambers, means for forcing heated air through the hot-air pipe or pipes into the said chambers, and valves for controlling the flow of hot air into the several chambers, for the purpose herein specified.

2. In an apparatus for drying and conserving fruits, the combination of drying or conserv-

ing chambers, steam heating pipe or pipes leading to the several chambers, steam pipe or pipes communicating with the interior of the several chambers, and valves for controlling the flow of steam through the latter pipes into the several chambers, for the purpose herein specified.

3. In an apparatus for drying and conserving fruits, the combination of drying or conserving chambers, steam heating pipe or pipes leading to the several chambers, steam pipe or pipes communicating with the interior of the several chambers, hot-air pipe or pipes communicating with the interior of the several chambers, means for forcing heated air through the hot-air pipe or pipes into the said chambers, and valves for controlling the flow of hot air and steam into the several chambers, for the purpose herein specified.

4. In an apparatus for drying and conserving fruits, the combination of drying or conserving chambers A, A, steam heating pipe or pipes B, leading to the several chambers, branch pipes *i i*, communicating with the interior of the several chambers, hot-air pipe or pipes C, communicating with the interior of the several chambers, exhaust pipe or pipes E, leading from the interior of the several chambers, exhaust fan or pump G, and valves *f g k* for controlling the flow of hot air and steam into and through the several chambers, substantially as and for the purpose herein specified.

In testimony whereof I affix my signature in presence of two witnesses.

DANIEL BURR.
